(57) **CLAIM**

What is claimed is a design for an excavator, as shown and described.

DESCRIPTION

FIG. 1 is a top left front perspective view of an excavator showing of the present invention;

FIG. 2 is a top right rear perspective view thereof;

FIG. 3 is a front view thereof;

FIG. 4 is a rear view thereof;

FIG. 5 is a left view thereof;

FIG. 6 is a right view thereof; and,

FIG. 7 is a top view thereof.
